UNITED STATES PATENT OFFICE.

GEORGE HAROLD DUNN, OF OAK PARK, ILLINOIS, ASSIGNOR, BY MESNE ASSIGNMENTS, TO THE SWEETS COMPANY OF AMERICA, INC.

DISPLAY BACK.

Application filed April 19, 1926. Serial No. 102,863.

This invention relates to display racks and particularly display racks for counter use adapted to hold vertical columns of packages of confections and sweets which are 5 removed one at a time preferably from the bottom of the column.

One of the objects of my invention is to provide a simple, economical, attractively made display rack of the above character 10 made of sheet metal of the minimum number of parts.

Another object of my invention is to provide a display rack of the above character made of sheet metal parts constructed and 15 arranged for simplicity and economy in manufacture and yet preserving a pleasing appearance to promote the vending of the confections mounted in the rack.

Another object of my invention resides in 20 providing a display rack wholly of sheet metal and constructed so as to eliminate raw edges as far as possible in consonance with the simplicity of the manufacture of the rack.

25 Still another object of my invention resides in providing a display rack adapted for built up construction so that the unit racks may be quickly assembled one to the other to provide a rack of greater capacity.

30 Other objects and advantages of the invention will be apparent as it is better understood from the following description, which taken in connection with the accompanying drawings discloses a further embodiment

35 thereof.

Referring now to the drawings which form part of this specification and in which like reference characters indicate corresponding parts,

40 Figure 1 is a perspective view of my improved rack,

Fig. 2 is a front view thereof,

Fig. 3 is a side view thereof.

Fig. 4 is a top view of the rack,

Fig. 5 is a section on line 5—5 of Fig. 3,

Fig. 6 is a section on line 6—6 of Fig. 2,

Fig. 7 is a section on line 7—7 of Fig. 6,

Fig. 8 is a section on line 8—8 of Fig. 3.

In general my improved rack comprises 50 two similar end members of sheet metal 1 and 2 which in the present form are somewhat triangular in shape with their apices uppermost and the bases of the triangular shaped portions denoted as 3 in the drawings 55 forming one of the members of the base of

the display rack. These side pieces 1 and 2 are formed with inwardly extending flanges 4 and 5 for constructional purposes as will be hereinafter explained, and the rearmost edges of these triangular shaped pieces are 60 turned inwardly as at 6 to avoid the presentation of rough or raw edges. The base of my improved rack comprises a substantially cradle shaped sheet metal piece, see Fig. 3, 65 which extends transversely between the two triangular shaped side pieces 1 and 2, such cradle shaped piece comprising a flat, horizontal portion 7 and two laterally bent flanges 8 and 9 the former of which extends upwardly, as shown in Fig. 3 of the drawings, and closes the bottom portion of the back between the two uprights 1 and 2. This cradle shaped piece has its flat, horizontal portion 7 overlying the flanges 4 and 5 of the end pieces 1 and 2 and is riveted 70 thereto as at 10 by means of which construction the cradle shaped member with its basal portion 7 together with the two side members 1 and 2 with their basal flanges 4 and 5 provide a substantially broad base upon which 75 my display rack rests. In this connection it will be noted that the forward, under surfaces of the flanges 4 and 5 are provided with outwardly bunched bumps or tits 11 upon 80 which these basal portions rest.

The confections in the form of vertical tiers are adapted to be held in upstanding, substantially inclined, shallow trays 12 and 13, as shown in Fig. 1. These trays are likewise formed of sheet metal, each comprising a relatively long sheet of metal bent to provide upstanding flanges 14 and 15 and an upwardly extending end flange which forms an outstanding shelf upon which the lowermost piece of confection rests when the tier is in 85 position in the tray. This shelf 16 and its function are shown clearly in Fig. 3 of the drawings. The front edges of these side pieces are bent forwardly to provide inwardly turned flanges 18 with curled under edges as 90 at 19. These opposed flanges 18 form guideways to prevent rolls of confection or other commodities from falling out of the rack. It will be noted that these flanges 18 terminate short of the tray or shelf 16 equal to the thickness of one of the confection rolls or commodities so that said roll or commodity may be extracted forwardly from the bottom of the tier. For the purpose of facilitating 95 the withdrawal of the lowermost commodity 105

the shelf 16 and the adjoining front face 12 of the rack are cut away as at 19 to provide a finger recess. Preferably the front edge of the shelf or tray 16 is curled backwardly as at 20 to avoid raw edges. Inasmuch as these trays are of duplicate construction, the foregoing description of the one will suffice. The juncture of the shelf portions 16 and the side members 14 is formed by suitably slotting the bottoms of the shelf members 16 and passing tongues 21 formed on the bottom ends of the side members 14 therethrough, as shown in Fig. 2 of the drawings. In addition the free ends of these shelf members 20 are bent over the sides of the members 14 to firmly hold the seams together. This construction is shown clearly in Fig. 6 of the drawings. The outer side pieces 14 are riveted to the triangular side portions, as at 22, so that the side pieces and trays are securely fastened throughout their length. In addition the trays are riveted to the front upstanding flange 9 of the cradle shaped portion by means of rivets 23, as indicated in Fig. 3 of the drawings. If desired the two adjacent side portions 14, as shown in Fig. 1, may be riveted together, as at 24.

The top of the trays are closed by means of a cap which extends as a single piece 25 entirely across the top of both trays. This piece is provided with a front downwardly extending flange 26 having an inturned edge 27 and in addition is provided with lateral ears 28 which overlap the side pieces 1 and 2 and also the sides 14 and 15 of the trays, all being riveted together as at 29. In addition there is provided an upstanding sheet metal piece or plate 30, riveted as at 31 to the back of the trays. This upstanding member forms a means for providing advertising indicia or the like.

The triangular side members of my rack are provided with means whereby they may be connected together in unit manner to similar display racks whereby the capacity of the rack may be increased in breadth. In the present invention this is accomplished by providing suitable bayonet shaped slots 31 and 32 on one of the side members and suitable correspondingly placed lugs 33 on the opposite side member.

The completed rack, suitably decorated, forms a most pleasing display rack for this type of confection wherein the entire stock of confections to be sold is presented at once to the eye and in such a manner that the commodities may be removed one at a time merely by inserting the finger under the lowermost piece of confection and withdrawing it from the vertical tier. In addition, by reason of the overhanging top or hood 25, the rack is more or less protected from dust and dirt. At the same time, by reason of the guide flanges 18, the commodity is prevented

from falling out of the rack until actually withdrawn.

One of the features of my invention resides in providing the background 12 and 13 of each of the trays with suitable advertising indicia arranged in lines thereon as, for instance, at 34, so that as each confection is withdrawn from the tier a fresh advertising indicia heretofore covered by the uppermost confection will be uncovered during the lowering of the tier of commodities. At the bottom of the tier is placed an indicia enjoining the dealer to refill the rack. This constitutes a very ingenious method of advertising.

It is thought that the invention and many of its attendant advantages will be understood from the foregoing description and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A device of the class described comprising a plurality of trays formed of sheet metal and bent to provide lateral upstanding flanges formed with inturned side members to provide guides, said side members terminating short of the extremities of said trays to provide filling and discharge apertures, the lower end of said trays having an upstanding ledge to support the lowermost piece of a tier of confections mounted in said trays, triangular shaped end pieces riveted to the upstanding flanges of said trays in a manner so that the basal portions of said triangular end pieces provide bottom supports for the display rack, a cradle shaped piece transversely disposed between said end pieces, said end pieces having inturned flanges folding over said cradle shaped piece and riveted thereto, said cradle shaped piece having a rearwardly positioned upstanding flange closing the lower rear space between said side pieces and said cradle shaped piece having a forwardly extending flange bent upwardly and riveted to the frontal faces of said trays, and a cap member extending continuously over the open top ends of said trays to close the same, said cap member having a downwardly extending flange extending over the upper open face of said trays, said cap member having laterally extending ears overlapping said end members and the upstanding ends of such trays and riveted together.

2. A device of the class described, comprising two trays formed of sheet metal and bent to provide laterally upstanding flanges each formed with inturned flanges terminating short of the extreme ends of the trays

to provide filling and discharge apertures, the bottom of said trays having outwardly extending flanges forming ledges for supporting tiers of confections mounted in the 5 trays, side members riveted to the lateral flanges of said trays, a basal member transversely disposed between said side members and riveted to inturned flanges formed on said side members, a top for said trays comprising a single piece of sheet metal extending thereacross and riveted to said end members, one of said end members being formed with bayonet slots and the opposite end member being formed with cooperating lugs 10 whereby each display unit may be assembled to a similar display unit to increase the capacity of the rack.

3. A sheet metal display rack for packages and the like consisting of the combination of a plurality of inclined shallow trays arranged side by side, triangular side members secured to the outer sides of the trays and forming a supporting base, a base member uniting said side members, and a top 15 member having a rear flange arranged behind the upper ends of said trays and having end flanges united with said side members, said trays having forwardly extending bottom flanges and side flanges partly overlying the trays, which side flanges terminate 20 below said top and above said bottom flanges to form entrances and exits for charging and removing goods from said trays.

4. A sheet metal display rack for packages and the like consisting of the combination of a plurality of inclined shallow trays arranged side by side, triangular side members secured to the outer sides of the trays and forming a supporting base, a base member uniting said side members, and a top 25 member having a rear flange arranged behind the upper ends of said trays and having end flanges united with said side members, said trays having forwardly extending bottom flanges and side flanges partly overlying the trays, which side flanges terminate 30 below said top and above said bottom flanges to form entrances and exits for charging and removing goods from said trays, and means for attaching similar racks at either 35 side of said display rack.

GEORGE HAROLD DUNN.
